UNITED STATES PATENT OFFICE.

FREDERICK E. BLAISDELL, OF PHILADELPHIA, PENNSYLVANIA, ASSIGNOR
TO THE BLAISDELL PAPER PENCIL COMPANY, OF PENNSYLVANIA.

PENCIL.

SPECIFICATION forming part of Letters Patent No. 549,952, dated November 19, 1895.

Application filed July 2, 1895. Serial No. 554,684. (No model.)

To all whom it may concern:

Be it known that I, FREDERICK E. BLAISDELL, a citizen of the United States of America, residing at the city of Philadelphia, in the county of Philadelphia and State of Pennsylvania, have invented certain new and useful Improvements in Pencils, of which the following is a specification, such as will enable those skilled in the art to which it applies to make and use the same.

The object of my invention is to provide a pencil of a new and improved form so constructed that the covering in which the marking-lead or crayon is inclosed may be removed from such marking-lead or crayon section by section, so as to uncover the said lead or crayon little by little as the same is worn away by use without the use of any cutting appliances whatever, in which the lead or crayon, while not secured in any manner to the covering material, cannot easily be drawn or pushed from its covering. This I accomplish by providing the marking-lead or crayon with a covering-film of any suitable material which is less lubric than the material of which the marking-lead or crayon is composed and inclosing such marking-lead or crayon so covered in a roll composed of a sheet of flexible material provided with a series of weakened lines arranged diagonal to the axis of the roll, all as shown and described in the following specification, of which the accompanying drawings form a part, wherein similar letters and numerals of reference designate like or equivalent parts wherever found throughout the several views, and in which—

Figure 1 is a view of one of such non-lubric-covered crayons or marking-leads about to be inclosed in a suitably-formed sheet of covering material. Fig. 2 is a view of a completed pencil of my improved form, showing a section of the covering material in the process of being stripped from the crayon or marking-lead. Fig. 3 is a view of such non-lubric-covered marking-lead or crayon in central longitudinal section thereof as the same appears at one stage of the process of manufacture thereof, and Fig. 4 is a view on an enlarged scale of the bottom portion or point-section of such non-lubric-covered crayon or marking-lead as the same appears when completed and ready for insertion in its covering.

Referring to the drawings, the reference-letter A designates the marking-lead or crayon; B, the non-lubric covering-film of such lead or crayon; C, the crayon-covering proper, and C' the sheet of flexible material out of which the crayon-covering C is formed when the pencil is to be of my improved self-sharpening form.

The sheet C' is preferably of what is known as "parchmentized paper" or of ledger paper, and such sheet is preferably of the same width as the lead is long and of sufficient length to form a roll of about the size of an ordinary lead-pencil when such sheet C' is rolled tightly around the marking-lead or crayon A. Running lengthwise of the sheet C' is a series of weakened lines 1, of any desired kind, preferably made by creasing or scoring upon one or both sides of the sheet, by perforation, or otherwise, by which the sheet C' is made easy of separation along each and every one of said lines 1 into narrow strips 2.

It will be seen from an examination of Fig. 1 that the sheet C' is of the form of a parallelogram having two obtuse-angled and two acute-angled corners, and such sheet is preferably provided adjacent to the edge which will form the outer edge of the covering roll with a series of perforations 3, which are preferably of the circular shape shown, of about the diameter of one-half the width of that of the strips 2, and preferably located, as shown, about half an inch from the strip C' and centrally of the weakened lines or scorings 1.

When the marking-lead or crayon A is formed of a highly-lubric substance, such as plumbago or a mixture of plumbago and other substances, and such crayon is inclosed in a roll formed of a sheet of flexible material, as C', as shown in Fig. 4, the extreme lubricity of the lead renders it easy to push or pull such lead or crayon from the inclosing roll. This of course is a great disadvantage in many ways, especially when the lead or crayon is from any cause broken into short pieces in the cover, and to overcome this I provide such lead or crayon with a non-lubric covering B, which may be applied thereto in any desired manner, preferably in the form of a liquid which will solidify thereon after being applied. This non-lubric covering-film B is preferably of copal varnish, applied to the crayon by dip-

ping the same in a vessel containing an extremely thin solution of such varnish, thinned by the addition of any suitable solvent thereof. After dipping, the crayon is suspended 5 with the point downward until the varnish has wholly dried thereon, and as the varnish is thin it will flow somewhat toward the lower end of the crayon, so as to form a bead 6, which covers the crayon - point, and before the 10 marking-lead or crayon is inclosed in its covering this bead is removed, preferably by immersing the lower end of such crayon for a half an inch or so in a bath of turpentine or other solvent of the varnish until such bead 15 has been dissolved from the crayon, so as to leave the point thereof bare. After the marking-lead or crayon has been provided with such non-lubric covering-film B the sheet C' is provided with a suitable edging of some adhesive substance—such as glue, paste, or the like—applied to such sheet along the entire end thereof outside of the line of perforations 3. The marking-lead or crayon so covered with the non-lubric film B is placed at the end of 20 the sheet C' which is opposite to that provided with the adhesive material, adjacent to which is the line of perforations 3, and such sheet C' is then rolled tightly around such marking-lead or crayon A into a roll, as shown 25 in Fig. 4, and as soon as the end provided with the adhesive substance comes in contact with the rest of the roll it adheres thereto, and after being allowed to dry the pencil is finished by sawing off the superfluous hollow 30 top portion, and may then, if desired, be varnished and otherwise ornamented upon the outside. When so formed, the pencil is from the first provided with a conical - pointed crayon-covering C, and as soon as the lead or 35 crayon point extending therefrom is worn down to such covering the lowest of the strips 2 adjacent to such point is started from the roll by tearing the same across adjacent to the first one of the perforations 3, at the point 40 marked 7 in Fig. 1, after which such strip is easily separated from the roll along the weakened line forming the upper boundary thereof by pulling upon the end so loosened, as shown 45 in Fig. 2, and when such strip is wholly removed from the crayon it will be found that 50 a section of the covering in the form of a conical helix has been removed therefrom and that a portion of the marking-lead or crayon A equal in length to the width of the strip 2 55 removed has been uncovered for use, and as this operation is successively repeated with each one of the strips 2 the crayon A is uncovered section by section as the same is worn away until the crayon has been almost entirely 60 used up and only a short stub is left formed of that portion of the crayon and covering C lying above the last perforation 3. The strips 2 may be separated between the perforations by the finger-nail or by the point of a pin 65 or any other suitable instrument having a point.

The non-lubric covering-film B does not ad-

here to the paper, but prevents the crayon from slipping in the covering C; yet at the same time it is so thin as not to interfere with 70 easy writing, and it wears away as fast as does the lead or crayon itself, and while, as before stated, I prefer to use copal varnish therefor, such film may be made of rubber, gelatine, or many other substances with equal 75 effect.

It will be seen that this pencil differs from others in which the crayon is provided with a covering-film of glue or other adhesive substances in that in the other forms of pencils 80 the covering-film adheres both to the crayon and to the covering, and in pencils provided with the covering of the form herein shown, which may be stripped from the crayon section by section, if such film adhered to the 85 covering as well as to the crayon such covering could not readily be stripped from the crayon, as the last layer of the covering, being glued tightly to the crayon, would have to be whittled or cut from the crayon before 90 the pencil could be used. If desired, however, even in my improved form of pencil, constructed as herein shown, the marking-lead or crayon may have its upper or butt end, or end farthest from the point, glued or otherwise secured to the covering for a short distance; but in all cases the working portion of the crayon (by which term I mean that portion of the crayon which is adapted to be uncovered and worn away by marking before 100 the pencil becomes too short for efficient use) is unattached to the covering-sheet C'; but as a crayon without a covering-film of non-lubric material, as herein shown, is shown and described in a former patent to myself, 105 hereinafter more particularly mentioned, as being so attached only at its upper end to the crayon-covering I have not deemed it necessary to show such construction herein.

Although I prefer in making a pencil of 110 the improved self-sharpening form shown to use parchmentized paper or ledger paper to form the crayon-covering C, there are many other substances—such as thin wood veneer, cloth, &c.—which may be used, and I do not 115 intend to confine myself to any particular substance either for the covering or for the marking-lead or crayon or for the film B, as it is evident that my invention is adapted for use with all kinds of chalks, crayons, caustics, 120 &c., and, in fact, any and all substances in the form of sticks which it is desired to uncover piece by piece, as well as for ordinary lead-pencils.

I do not claim herein, broadly, the self-sharpening pencil having a covering of paper, for the reason that the same is fully shown, described, and claimed in United States Letters Patent No. 461,911, granted to me October 27, 1891, for an improvement in pencils. 125

It is evident that many changes in the construction, combination, and arrangement of the several parts of my invention other than those mentioned may be made without de-

parting from the scope thereof, and I do not intend to limit myself to any particular construction either of my improved pencil or my improved crayon; but,

5 Having now particularly described my said invention, what I claim, and desire to secure by Letters Patent, is—

1. A pencil having its marking-lead or crayon provided with a covering-film B of less 10 lubricity than the crayon and inclosed in a roll composed of a sheet of flexible material C' weakened at intervals, the film B being unattached to the sheet C' throughout the working length of the crayon, substantially as described and for the purposes set forth.

2. A pencil having its marking-lead or crayon provided with a covering-film B of less lubricity than the crayon and inclosed in a covering from which sections in the form of a 20 conical-helix may be removed one by one so as to uncover the marking-lead or crayon section by section, the film B being unattached to the sheet C' throughout the working-length of the crayon, substantially as described and for the purposes set forth.

3. A pencil having its marking-lead or crayon provided with a covering-film B of less lubricity than the crayon and inclosed in a roll composed of a sheet of flexible material 30 C' bearing weakened lines arranged diagonal to the axis of the roll along which the sheet may be separated, the film B being unattached to the sheet, substantially as described and for the purposes set forth.

35 4. A pencil having its marking-lead or crayon provided with a covering-film B of less

lubricity than the crayon and inclosed in a roll composed of a sheet of flexible material bearing weakened lines arranged diagonal to the axis of the roll, along which the sheet may 40 be separated, the outer edge of the sheet being secured to the roll, and the film B being unattached to the sheet, substantially as described and for the purposes set forth.

5. A pencil having its marking-lead or 45 crayon provided with a covering-film B of less lubricity than the crayon and inclosed in a roll composed of a sheet of flexible material bearing weakened lines arranged diagonal to the axis of the roll, the film B being unat- 50 tached to the sheet throughout the working length thereof, the outer edge of the sheet being secured to the roll and being provided with perforations 3 adjacent to such edge, substantially as described and for the pur- 55 poses set forth.

6. A pencil having its marking-lead or crayon provided with a covering-film of less lubricity than the crayon and inclosed in a covering which may be removed section by 60 section from the crayon without the use of a cutting instrument, the covering-film being unattached to the covering, substantially as described and for the purposes set forth.

Signed in the city and county of New York, 65 in the State of New York, this 11th day of June, A. D. 1895.

FREDERICK E. BLAISDELL.
